(57) **CLAIM**

The ornamental design for footwear sole, as shown and described.

DESCRIPTION

FIG. 1 is a perspective view of the shoe sole embodying the new design;

FIG. 2 is a bottom elevational view thereof;

FIG. 3 is a right side elevational view thereof;

FIG. 4 is a left side elevational view thereof;

FIG. 5 is a front elevational view thereof; and,

FIG. 6 is a rear elevational view thereof.

FIGS. 1 and 3-6 show portions of an upper in broken lines.
The broken lines are for environmental purposes only and
form no part of the claimed design.
